UNITED STATES PATENT OFFICE.

ALMYR L. NEWMAN, OF WARWICK, RHODE ISLAND, ASSIGNOR TO A. L. NEWMAN COMPANY, OF CRANSTON, RHODE ISLAND, A CORPORATION OF RHODE ISLAND.

ATTACHING MEANS FOR NAME PLATES AND OTHER ARTICLES.

Application filed February 3, 1926. Serial No. 85,708.

This invention relates to improved means for attaching name-plates, emblems, medallions or other devices to any certain object, particularly for attaching manufacturers' 5 name-plates or insignia-bearing devices to the radiator shells of motor vehicles.

A principal object of the invention is to provide means whereby the name-plate or other device may be fastened securely in 10 place on the front of the radiator shell or other structure by forcing its attaching means into a depression or orifice therein.

Another object of the invention is to provide an attaching means which will lock the 15 name-plate or other device permanently in place on the shell or other structure to prevent its accidental release under jar or vibration, and also to prevent it from being pried off.

Another object of the invention is to provide an attaching means for the name-plate or other article which may be more readily and conveniently applied to use without requiring skill or expertness on the part of 20 the workman or the use of tools.

Another object of the invention is to provide an attaching and locking means for the name-plate or other article which is simple in construction, more economical to manufacture and generally more efficient and durable in use.

Further objects of the improvement are set forth in the following specification which describes a preferred embodiment of the invention as illustrated by the accompanying drawings. In the drawings:—

Fig. 1 is a perspective view of a portion of the hood of a motor vehicle showing a conventional form of name-plate or emblem applied to its radiator shell;

Fig. 2 is a vertical sectional view taken through the center of the radiator shell and illustrating the attaching means on the name-plate as being entered into the orifice 40 in the shell;

Fig. 3 is a similar sectional view showing the name-plate seated in a recess on the front of the shell with the attaching means forced into the orifice thereof to lock the plate in 45 position;

Fig. 4 is a view of the back of the name-plate or emblem showing the construction of the attaching means which projects therefrom;

Fig. 5 is a perspective view of the resilient

ring or annulus which acts as the locking or gripping device for the attaching means; and

Fig. 6 is an enlarged plan view showing the means for fastening together the ends of 60 the helical coil constituting the gripping means.

The present invention consists in general in providing the name-plate or other article to be attached with a resilient ring or annulus connected thereto in such manner that it will be compressed when forced into the orifice in the radiator shell or other structure, whereby its inherent spring tendency 65 will cause it to impinge against and frictionally grip the interior walls of the orifice to hold the plate securely in position on the shell.

In Fig. 1 of the drawings S designates the sheet-metal shell or shield which encloses the 70 top and sides of the cellular radiator-structure R on most types of motor vehicles, and to the front of which is usually attached a name-plate, medallion or other ornamental insignia-bearing device P. The name-plate 75 or emblem P may be constructed as a sheet-metal stamping and is generally embossed, enameled or otherwise ornamented on its face. It is the preferred practice to attach such devices to the radiator shell without the use of solder, rivets, screws, or other means

necessitating mechanical operations either before or after the shell has been assembled on the radiator. For this purpose various 80 types of concavo-convex, coniform and irregularly-shaped deformable disks and rings have been employed, but most of these have 85

not been found entirely satisfactory to effect a secure and permanent bond between the plate and the radiator shell. In the present 90 improvement the attaching means is not dependent on the distortion or deformation of the locking element to provide the gripping action, the gripping member being inherently capable of contraction and expansion 95 without distortion and therefore without liability of weakening or rupturing the metal from which it is constructed.

As shown in the present drawings the insignia-device or emblem P takes the form of a substantially flat plate of hexagonal outline. In other examples, however, it may be of different contour and in some cases of generally concavo-convex shape in cross-section. In some instances it may be held flat 100 105 110

against the front of the radiator shell S, while in others it may be seated in a recess or depression s as illustrated most clearly in Fig. 3. The front of the radiator shell S is provided with an orifice 2 which may be formed by flanging the metal inwardly in a cylindrical rim or annulus 3.

As one embodiment of the present invention, the back of the plate or emblem P is provided with a channeled flange or annulus 4 having an outside diameter slightly less than the inside diameter of the orifice 2 to adapt it to slide freely thereinto. Conveniently, the flange or annulus 4 may be constructed of sheet-metal with an outwardly flaring rim 5 at one side thereof which is adapted to be soldered, brazed, welded or otherwise suitably secured to the back of the plate or emblem P. The opposite or outer edge of the annulus 4 is also swaged or formed into an upstanding flange or rim 6 which merges into the main portion of the annulus 4 with a rounded contour. In this way the annulus 4 is provided with a peripheral trough or channel adapted to receive the spring-ring or annulus 7 which acts as the locking means for the name-plate.

The spring-ring or annulus 7 is shown in perspective in Fig. 5 of the drawings, and preferably it consists of a helically wound strip or wire 8 having the ends joined together to provide a continuous flexible band or strap. Preferably, the strip or wire 8 from which the annulus is constructed is of square or rectangular cross-section, and the coils or loops of the helix are flattened on their longitudinal axis, as indicated more particularly in Figs. 2 and 3. The ends of the wire 8 in the continuous coil or helix 7 may be secured together in any suitable manner, a convenient method being shown in Fig. 6. As here illustrated a rectangular metal strip or plate 10 is inserted through the end loops or coils of the helix and provided with slits or apertures 11 through which the terminal portions 12 of the wire 8 are projected and bent over or riveted on the opposite side as shown in Fig. 5. Through this means the ends of the band or helix are effectually secured together to form the continuous ring or annulus. The circular ring or annulus 7 is susceptible of considerable expansion to adapt it to be stretched over the fixed ring or annulus 4 on the back of the name-plate P, and its inherent spring tendency will cause it to contract to seat snugly in the channel thereof as shown in Figs. 2, 3 and 4. At the same time, the individual loops or coils of wire in the annulus 7 have sufficient rigidity to normally maintain them in the shape illustrated in Fig. 2, with the outer periphery of the annulus of slightly larger diameter than the interior of the orifice 2 in the radiator shell S.

To attach the name-plate or device P to the front of the radiator shell S the inner rim of the rigid annulus 4 is entered into the mouth of the orifice 2, as shown in Fig. 2, and by exerting sufficient pressure on the front of the name-plate the attaching means may be forced back into the flange 3 until the plate P seats in the depression s on the front of the shell. As the attaching means is forced into the orifice 2 the coils or loops of the flexible annulus 7 will be compressed or flattened in the manner illustrated in Fig. 3. This compression of the helix causes it to bind firmly against the bottom and side flanges of the fixed annulus 4, while its peripheral surface will be forced into frictional engagement with the inner walls of the orifice 2 to securely grip the latter.

This gripping action of the flexible and contractible annulus 7 on the interior of the flange 3 of the radiator shell S provides a substantially positive locking or dogging action which effectually prevents withdrawal of the attaching means from the orifice under considerable stresses and strains. Moreover, the relatively sharp lateral edges of the coils or loops of wire in the helix bite against the interior walls of the orifice 2 to prevent the name-plate from being turned or rotated with respect to the shell. In this way the name-plate, emblem or other device is securely fastened in position to prevent its release under jar, vibration or other strain, and also to hold it against turning to prevent it from becoming misplaced on the radiator shell.

With the improved attaching means as above described it is practically impossible to remove the name-plate from the radiator shell even with a prying action under its edge, the joinder between the plate and the structure to which it is attached being substantially permanent and unyieldable for all time.

The improved attaching means is extremely simple in construction, convenient and economical to manufacture, and does not require accurate machining or other operations to render it capable of fitting the orifice. Furthermore, the attaching means is self-adjustable and self-conformable, so that if the size or shape of the openings or orifices in the radiator shells varies to any degree it will not diminish or impair the gripping effect of the attaching means. The improved device is therefore much easier to construct and apply to use and practically universally adaptable for all types of radiator shells or other structures to which the name-plate or other article is to be attached.

While I have herein illustrated a preferred form of construction of the improved device, it is obvious that various modifications may be made therein without departing from the spirit or scope of the invention.

Therefore, without limiting myself to the exact details as herein shown and described I claim:—

1. Means for attaching a name-plate or other article to another object or structure having an orifice, comprising in combination with such article, a contractible annulus mounted thereon and constructed with loop-like spring-elements adapted to be compressed when the annulus is forced into the orifice to cause it to frictionally grip the interior thereof to resist withdrawal or dis-
placement of the article.
2. Means for attaching a name-plate or other article to another object or structure having an orifice, comprising in combination with such article, a contractible annulus mounted thereon and consisting of a helically coiled band having a peripheral circumference greater than that of the orifice to adapt it to be forced thereinto to cause it to frictionally grip the interior thereof.

3. Means for attaching a name-plate or other article to another object or structure having an orifice, comprising in combination with such article, a rigid annulus on the article, and a contractible annulus consisting of a helical coil surrounding the rigid annulus and susceptible of being constricted when forced into the orifice to adapt it to frictionally grip the interior thereof.

4. Means for attaching a name-plate or other article to another object or structure having an orifice, comprising in combination with such article, a rigid annulus projecting therefrom and provided with a circumferential channel, and a helically coiled band seated in the channel surrounding the annulus, and adapted to be compressed when forced into the orifice to cause it to frictionally grip the interior thereof.

In testimony whereof I affix my signature.

ALMYR L. NEWMAN.
